UNITED STATES PATENT OFFICE.

WILLIAM FRANCIS MEEK, OF TAMPICO, MEXICO.

BARREL-PROTECTOR.

1,399,569.

Specification of Letters Patent.

Patented Dec. 6, 1921.

Application filed October 19, 1920. Serial No. 417,950.

To all whom it may concern:

Be it known that I, WILLIAM FRANCIS MEEK, a citizen of the United States, and resident of Tampico, Tamps, Mexico, have 5 invented a new and Improved Barrel-Protector, of which the following is a full, clear, and exact description.

My invention relates to a receptacle protector, and aims to provide a device of this 10 nature, more particularly adapted for use in connection with barrels, and by means of which the latter will be braced and generally strengthened to withstand the shocks incident to handling.

15 It is well appreciated, that receptacles, and more particularly barrels, are subjected to numerous strains incident to transportation. This is particularly the case where a keg or barrel receives a relatively 20 heavy substance, or fluid, such as oil.

In handling, while being transported, these receptacles receive extremely hard usage, particularly so that it often times 25 happens that the side walls, or heads of the barrels are injured to an extent permitting escape of the contents.

This injury is estimated as resulting in 30 a loss of fully 15% of substances, and particularly fluids transported by this method, and with this in view, it has been proposed to provide an exterior bracing, in the nature of a crate, around the barrels or receptacles, but this crating has not served 35 its object, in that it is primarily, expensive, secondly any foreign object passing between the bars or rods forming the crating would result in the same damage as if the barrel were entirely unprotected. Further, the crating has proven impractical in that more 40 space is occupied by a receptacle having the same in applied position thereon, so that shipments become more expensive by virtue of the additional space required in handling the same number of receptacles.

45 Having the foregoing in mind, I have now constructed a protector applicable to any type of receptacle, for receiving any kind of substance or fluid, and by means of which the side walls and heads of the same 50 will be protected from injury.

A further object of my invention is the provision of a device of this nature, which shall not exceed the space occupied by a receptacle not having the same applied, so that the 55 objection heretofore enumerated is avoided,

A still further object of my invention is the construction of a protector which may be manufactured with a minimum of cost, and shall embody a simplicity of structure, permitting of its instantaneous application. 60

Further objects of my invention will appear in the annexed specification and drawings, which latter represent one practical embodiment of my invention, and in which—

65 Figure 1 is a sectional side view taken through a protector constructed in accordance with my invention, and showing the same in applied position within a receptacle of the nature specified, the latter being indicated in dotted lines.

Fig. 2 is a sectional plan view taken along the line 2—2 of Fig. 1.

Fig. 3 is a side view of one of the units forming a part of my protector, and 75

Figs. 4 and 5 illustrate the upper and lower units providing the end portions of my improved device.

In these various views, the reference numeral 10 indicates what is termed the head 80 protector, with which the various parts going to make one complete unit of the device are associated. For convenience sake, I shall designate one of the units, the association of this unit with the second unit being 85 specifically brought out.

It will now be noted, reference being had to Fig. 3, that I conveniently use a pair of staves 11, which staves conform to the interior contour of the receptacle 12, and 90 which have one of their ends secured to the head protector 10 in any desired manner, at diametrically opposite points.

Secured to the opposite end of the staves, is what might be termed the body protector. 95 This latter device preferably includes two portions, each comprising a semi-circular body 13 and a transversely extending bar 14, having its ends secured to the ends of the semi-circular body 13. The brace 15 is conveniently associated with each of the body portions, and has its ends engaging the body 13 and bar 14 respectively, at points approximately intermediate their extremities.

As aforesaid, two main portions, comprise the completed body protector, and, as has been illustrated clearly in Figs. 1 and 2, it will be seen that the bars 14 of the two portions are brought to a position at which their exterior faces contact one with each 110

other, in which position they are secured together, by any suitable means such as transversely extending bolts 16.

It is now to be noted that the outer side edges of the head protector 10 and body 13, of the body protector, are conveniently inclined, as has been indicated in Figs. 1 and 3, to conform to the interior contour of the receptacle 12. It will also be seen that each of the bodies 13 is provided in its interior face with a groove 17, at a point preferably 90° from the point at which the end of each of the staves 11 is secured.

The bodies of the staves 11 form a part of opposite units, and are now slidably arranged within these grooves, and it will be appreciated, that by this provision that an action may be set up which might be termed "telescopic". In practice, it will be appreciated that a protector constructed in accordance with my invention is conveniently associated with the receptacle 12, while in course of manufacture, but it will also be understood that this protector is capable of association with a receptacle subsequent to its manufacture, which would be desired, as for instance, where my improved protector was to be applied to an already constructed receptacle. The body protectors may readily be assembled within the body of the barrel, so that no difficulty, incident to inserting the same through the neck of the barrel may be experienced in view of the relatively large diameter of the body protectors when assembled.

In any instance, subsequent to the complete assemblage of the protector structure, the entire device may be extended, so as to bring the staves 11, edges of the body portion 13, and head protectors 10 into intimate engagement with the interior face of the receptacle, or by strengthening the latter to a maximum extent, so that the damage liable to occur in handling is reduced to a minimum, and the consequential loss of the contents of the receptacle is prevented.

Thus it will be seen that I have provided a protector which is extremely economical in structure, which may be quickly applied to a barrel, and which will serve to prevent the damage heretofore experienced in connection with the shipment of this class of receptacle. It will also be seen that the protector may be manufactured in one size, but due to the telescoping action of the parts of the same, that the device is adapted to varying sizes of receptacles, within the limits of its extensible motion.

Obviously numerous modifications of structure might readily be resorted to without in the least departing from the spirit of my invention, which I claim as—

1. A protector for receptacles, including in combination with a receptacle comprising

bulged side walls, and head attached adjacent the ends of said side walls, of means, of a fixed diameter within said receptacle, said means being longitudinally extensible to permit of the contacting of the same with the interior face of said receptacle upon being extended.

2. A protector, including in combination, a pair of units adapted to be positioned within a receptacle, each of said units comprising a head protector and body bracing portion, and means for connecting the parts of said units together.

3. A protector, including in combination, a pair of units adapted to be positioned within a receptacle, each of said units comprising a head protector and body bracing portion, means for connecting the parts of said units together, and means permitting a telescoping action on the part of said units, one with respect to the other.

4. A protector, including a pair of members each comprising a head protector and body bracing portion, and staves extending between and having their ends secured one to each of said members.

5. A protector, including a pair of members each comprising a head protector and body bracing portion, staves extending between and having their ends secured one to each of said members, and being in slidably engagement with one of the parts of the opposite unit.

6. A protector, including a pair of members each comprising a head protector and body bracing portion, staves extending between and having their ends secured one to each of said members, the body bracing portions of each unit comprising a pair of semi-circular bodies, and a transversely extending bar having its ends secured to the ends of said body portion, the bars of each of said body portions being adapted to be secured together.

7. A protector, including a pair of members each comprising a head protector and body bracing portion, staves extending between and having their ends secured one to each of said members, each of said body bracing portions including a circular body formed with grooves in its outer edge adapted to slidably accommodate the staves of the opposite unit.

8. A protector, including a pair of members each comprising a head protector and body bracing portion, staves extending between and having their ends secured one to each of said members, said heads and body bracing portions being formed with inclined side edges adapted to conform to the interior contour of the receptacle with which the protector is associated.

WILLIAM FRANCIS MEEK.
